MICROTOME ANTI-ROLL DEVICE

James B. McCormick, La Grange, and Leighton C. Johnson, Westmont, Ill., assignors to Miles Laboratories, Inc., Elkhart, Ind., a corporation of Indiana

Filed Sept. 29, 1964, Ser. No. 399,982
7 Claims. (Cl. 83—109)

The present invention relates to the preparation of specimen for microscopic examination. More particularly, it relates to an improved method and apparatus for removing a very thin section from a specimen.

In the microscopic examination of certain specimen such as, for example, specimen of animal tissue or the like, it is customary to remove from the specimen a number of thin slices or sections which are then placed on a transparent slide for viewing in a microscope. Frequently, the section is only a few microns in thickness; hence, it lacks structural strength and, as a result, has a tendency to curl or roll into a cylinder as it is being formed, thus rendering it unsuitable for mounting on a slide. A curled or rolled section can occasionally be straightened and used, but more often it breaks when an attempt is made to straighten it due to its extreme thinness.

In many cases, a section curls because the specimen has been improperly prepared or because the microtome has been improperly adjusted. Both of these factors are critical. To slice a section and avoid curling, a technician usually must have considerable experience. Without such experience, a technician generally must employ a time consuming trial and error procedure. Oftentimes, as during a surgical operation, time is of a premium and cannot be spared.

In many instances, one solution to the problem of curling has been to use a soft sable brush to stroke the section and keep it flat as it is formed. This technique requires a very delicate touch and is considered unsatisfactory as a general practice because of its tendency to damage the section, and because of the difficulty in operating the microtome and manipulating the brush at the same time. Therefore, improvements in this technique are desirable.

The principal object of the present invention is to provide an improved method of removing a thin section from a specimen. Another object is to provide a device capable of preventing a curling of a section as it is removed from the specimen. These and other objects of the invention are more particularly set forth in the following detailed description and in the accompanying drawings wherein:

FIGURE 1 is a perspective view of a microtome and device showing various of the features of the invention;

FIGURE 2 is a fragmentary sectional view of the microtome as viewed in the direction of the arrows 2—2 of FIGURE 1;

FIGURE 3 is an enlarged perspective view of a portion of the device shown in FIGURE 1; and

FIGURE 4 is a diagrammatic view generally similar to that of FIGURE 2 but showing the microtome of FIGURE 1 as a section is being sliced from a specimen.

In general, the present invention is directed to that step in the preparation of a specimen for microscopic examination in which a thin section is sliced from the specimen. In accordance with the invention, the section is prevented from curling by the constant application of mechanical pressure to that portion of the specimen first to be removed from the specimen in the form of a section. In the illustrated embodiment, this mechanical pressure is provided by means of a device 11 mounted on a microtome 13 by means of which the sectioning is accomplished.

2

Referring now to the drawings, the microtome 13 may be of various constructions but, in the illustrated embodiment, comprises a base 15 and a specimen carrier 17 mounted on the base for vertical reciprocal movement as imparted by a manually operated drive mechanism (not shown). The specimen carrier 17 comprises a chuck 19 and a specimen support 21, the chuck 19 being in the form of a block centrally recessed to provide an opening within which the specimen support may be placed. The specimen support 21 may take the form of a flange metal plate, as in the illustrated embodiment, but might also be in the form of a paraffin block within which the specimen is embedded. In either event, the support 21 is held in place within the opening of the chuck 19 by a movable jaw 23 suspended adjacent the lower edge of the chuck and rendered movable in a vertical direction relative to the chuck by a knob 25.

Slidably mounted on the base 15 is a horizontally disposed plate 27 having a pair of depending lugs 29 which support a knife blade 31. The plate 27 is so connected to the driving mechanism of the chuck 19 that each time the chuck is moved through a vertically reciprocating cycle, the plate 27 is moved so as to advance the knife an incremental distance in the direction of a specimen 33 supported by the chuck. This incremental degree of advancement is equal to the desired thickness of the section 34 and is controlled by an adjusting knob 35 at the side of the microtome. Substantial movement of the knife blade relative to the chuck, as for adjustments and the like, is effected by a feed wheel 37.

The anti-roll device 11 is preferably mounted on the microtome 13 and, in the illustrated embodiment, is secured to the specimen carrier 17 of the microtome. However, the device might also conceivably be supported on other portions of the microtome as, for example, on the knife 31. The device 11 prevents curling or rolling of the section 34 by engaging that portion of the specimen which is the first to be removed from the specimen in the form of a section and urging it into contact with a face of the knife 31 as the section is cut.

Very generally, the device 11 comprises a U-shaped bail 39 connected by means of a hinged supporting structure 41 to the chuck 19 of the specimen carrier 17 so as to render the device movable with the carrier but stationary with respect to the specimen itself. In the illustrated embodiment, the bail is positioned so that before the cut is initiated, it will be in engagement with that portion of the face of the specimen immediately above the lower edge thereof. As the cut is made, the portion engaged by the bail 39 becomes the portion of the section 34, which is then urged by the bail against the face of the knife 31.

More specifically, the hinged supporting structure 41 comprises a hinge strap 43 which is secured, as by machine screws, to the upper surface of the chuck 19. The hinge strap 43 carries a pair of upwardly disposed knuckles 45 which pivotally mount a support element 44. A pair of ears 48 project upwardly from the opposite ends of the strap and are adapted to engage the element 44 and permit it to be maintained in a raised out-of-the-way position for insertion and removal of the specimen support from the chuck.

The support element 44 is tubular in construction and is generally U-shaped so as to include a base leg 49, which is rotatably journaled in the knuckles 45, and a pair of outer legs 51. A sleeve 53 is crimped to the central portion of the base leg 49 and holds the support element 44 centered with respect to the hinge strap 43. The legs 51 are bent intermediate their ends so as to form approximately a 60° angle and thereby locate the outer portions of the legs adjacent to the specimen support 21. A handle 55 is secured to one of the legs and projects out-

wardly past the apex or bend thereof to facilitate manipulation of the support element.

The bail 39 is in the form of a thin wire bent into a U-shape so as to include a central portion or bar 57 which engages the specimen 33 and, later, the section 34, and a pair of generally parallel arms 59 which are proportioned to telescope within the end portions of the tubular legs 51 of the support element 44. Preferably, the resiliency of the wire of the bail is such that when the arms 59 are bent slightly out of parallel, the friction between the arms 59 of the bail and the end portions of the legs 51 of the tubular support element 44 is sufficient to hold the bail in any degree of extension relative to the legs. This adjustability of the bail allows it to be maintained at any desired level adjacent the lower portion of the front surface of the specimen 33, thus obviating the need for precise positioning of the specimen on the specimen support 21. This feature is particularly advantageous in the frozen specimen technique in which a specimen is frozen to the surface of the support 21, as in the illustrated embodiment.

In the use of the device 11, a specimen support 21 carrying a specimen 33 is placed within the chuck 19 of the microtome 13. During such placement, the supporting structure 41 and bail 39 are pivoted to a raised position and maintained in such position by the ears 48 located at opposite sides of the hinge strap 43.

With the specimen support in place, the supporting structure and bail are lowered so as to place the bar 57 of the bail in the vicinity of the outer face of the specimen 33. The bail 39 is then telescopically adjusted so as to place the bar in engagement with that portion of the front face of the specimen which is located just above the lower edge of the specimen (see FIGURE 4). Sectioning is now ready to proceed.

As the microtome is operated, the chuck 19 moves downwardly so as to effect cutting engagement between the specimen and the knife 31, thereby initiating the cutting of a thin slice or section from the specimen (diagrammatically illustrated in FIGURE 4). During this initial cutting, the section 34 is moved outwardly away from the specimen, but the arrangement of the bail and support 21 provides a gravity bias which maintains the bar 57 in contact with the lower edge of the section. As particularly shown in FIGURES 2 and 4, the gravity bias includes two components, one of which is directed downwardly on the section being removed from the specimen, and the other of which is directed inwardly on the section toward the specimen. Thus, the weight of the bail bears downwardly and inwardly against the front face of the knife blade 31 and prevents initial curling of the section.

As the chuck 19 continues to move downwardly, thereby causing the blade edge to penetrate further into the specimen, the supporting structure 41 and bail 39 pivot slightly upwardly. The continued engagement of the bar 57 of the bail with the edge of the section continues to prevent the section from curling. In addition, surface tension developed between the section and the face of the knife further reduces the tendency of the section to curl.

After the blade 31 has passed completely through the specimen 33, the bar 57 of the bail 39 may pass off the face of the lower edge of the knife and thus become disengaged from the section. However, at this point the tendency of the section to curl has been essentially overcome, and any tendency which remains is compensated for by surface tension. The bail 39 may then be lifted over the knife blade as the chuck 19 is raised and be placed again in contact with the face of the specimen, as before, for the cutting of another section.

The device 11 thus prevents curling of the section and is effective even if other factors which influence the sectioning operation, e.g., the preparation of the specimen and the adjustment of the microtome, are not ideal. The device is uncomplicated and can be utilized by technicians

of modest experience. It is of simple construction and can be economically produced, yet is durable and not readily subject to breakage or malfunction.

Various of the features of the invention are set forth in the appended claims.

What is claimed is:

1. A microtome comprising a supporting base, a carrier mounted on said base adapted to support a specimen, a microtome knife mounted on said base adjacent said carrier adapted to slice sections from a given face of a specimen supported on said carrier incident to a predetermined engagement between said specimen and knife, means for causing relative movement between said carrier and said knife so as to effect said predetermined engagement, and a device positioned adjacent said carrier for preventing curling of a section sliced from the specimen, said device including means for mechanically engaging only a single line along the surface of the section as it is being sliced from the specimen, said member being pivoted about an axis located on the opposite side of the cutting plane from said section and vertically above the upper level of a specimen frozen to said specimen carrier so as to cause said member to bear downwardly and inwardly against the surface of the section so as to urge the section against the face of the knife blade and thereby prevent the section from curling.
2. A microtome comprising a supporting base, a carrier mounted on said base adapted to support a specimen, a microtome knife mounted on said base adjacent said carrier adapted to remove sections from a given face of a specimen supported on said carrier incident to a predetermined engagement between said specimen and knife, means for causing relative movement between said carrier and said knife so as to effect said predetermined engagement, and a device positioned adjacent said carrier for preventing curling of a section sliced from the specimen, said device including a member pivotally mounted adjacent said carrier and said knife and adapted to pivot between a first out of the way position permitting complete access to the carrier to permit the mounting of a specimen thereon and a second position in contact with that portion of the specimen first to be removed from the specimen in the form of a section, said member being adapted to remain in contact with the section as the section is being removed from the specimen, said member being pivoted about an axis located on the opposite side of the cutting plane from said section and vertically above the upper level of a specimen frozen to said specimen carrier so as to cause said member to bear downwardly and inwardly against the surface of the section so as to urge the section against the face of the knife blade and thereby prevent the section from curling.
3. A microtome comprising a supporting base, a carrier mounted on said base adapted to support a specimen, a microtome knife mounted on said base adjacent said carrier adapted to remove sections from a given face of a specimen supported on said carrier incident to a predetermined engagement between said specimen and knife, means for causing relative movement between said carrier and said knife so as to effect said predetermined engagement along a cutting plane, said knife being mounted with the face of the blade against which said sliced specimen will bear being disposed at an angle from said cutting plane, and a device positioned adjacent said carrier for preventing curling of a section sliced from the specimen, said device including a member pivotally mounted on said specimen carrier and adapted to assume a position in contact with that portion of the specimen first to be removed from the specimen in the form of a section, said pivot point being on the opposite side of the cutting plane from the side of the sliced section said member being adapted to remain in contact with the section as the section is being removed from the specimen said member being pivoted so as to bear downwardly and inwardly against the section

so as to urge the section against said face of said knife blade and thereby prevent the section from curling.

4. A microtome comprising a supporting base, a carrier mounted on said base adapted to support a specimen, a knife mounted on said base adjacent said carrier adapted to remove sections from a given face of a specimen supported on said carrier incident to a predetermined engagement between said specimen and knife, means for causing relative movement between said carrier and said knife so as to effect said predetermined engagement, and a device positioned adjacent said carrier for preventing curling of a section sliced from the specimen, said device including a bail having a central horizontal bar and a pair of flanking arms, support means telescopically mounting said arms of said bail, means pivotally mounting said support means on the specimen carrier so that said bar may be moved between a lower position wherein it gravitationally bears against the front surface of the specimen and an upper position spaced away from the specimen, and means for frictionally retaining said support means in said upper position.

5. A microtome comprising a base, a specimen carrier mounted on said base, a specimen support adapted to support a frozen specimen, means attaching said specimen support to said specimen carrier, a microtome knife adapted to slice sections from a given face of a specimen frozen to said support incident to a predetermined engagement between said specimen and knife, means for causing relative movement in a generally vertical direction between said carrier and said knife so as to effect said predetermined engagement, means mounting said microtome knife on said base with the cutting edge pointing generally upward and with the upper face of the blade disposed at an angle from the cutting plane which plane is established by the direction of said relative movement, and a device pivotally mounted on said carrier for preventing curling of a section sliced from the specimen, said device including a member adapted to contact that portion of the specimen first to be removed from the specimen in the form of a section, said member being adapted to remain in contact with the section as the section is being removed from the specimen, said member being pivoted so as to bear downwardly and inwardly against the section so as to urge the section against said upper face of said knife blade and thereby prevent the section from curling, said pivot point of the mounting being on the opposite side of the cutting plane from said section and at a point vertically above

the upper level of a specimen frozen to said specimen support.

5 6. A microtome comprising a supporting base, a carrier mounted on said base adapted to support a specimen, a knife mounted on said base adjacent said carrier adapted to slice sections from a given face of a specimen supported on said carrier incident to a predetermined engagement between said specimen and knife, means for causing relative movement between said carrier and said knife so as to effect said predetermined engagement, and a device positioned adjacent said carrier for preventing curling of a section sliced from the specimen, said device including a generally horizontally disposed thin bar and an arm at one end of said bar, support means telescopically mounting said arm to support said bar at different vertical levels, means pivotally mounting said support means on the specimen carrier so that said bar may be moved between a lower position wherein it gravitationally bears against the front surface of the specimen and an upper position spaced away from the specimen.

10 7. A device for use with a microtome and adapted to prevent curling of a section sliced from a specimen by means of the microtome, which device comprises a thin bar adapted to be placed to bear only along a line of contact with that portion of the specimen which is first to be removed from the specimen in the form of a section, and pivot means mountable on the microtome adapted to pivotally support said bar and maintain it in contact with the above-mentioned portion of the specimen during the formation of the section as the section slides along the face of a knife blade disposed at an angle to the cutting plane along which the section is severed from the specimen, the pivot point being on the opposite side of the cutting plane from the first-removed portion of the specimen, said bar thereby being pivotally supported so as to bear downwardly and inwardly against said first-removed portion of the specimen so as to urge it against the face of said knife blade.
